UNITED STATES PATENT OFFICE.

AXEL HELMER ENGLUND, OF CHICAGO, ILLINOIS.

CLAMP FOR ELECTRIC CONDUCTORS.

SPECIFICATION forming part of Letters Patent No. 498,776, dated June 6, 1893.

Application filed June 29, 1891. Serial No. 397,862. (No model.)

To all whom it may concern:

Be it known that I, AXEL HELMER ENGLUND, of Chicago, in the county of Cook and State of Illinois, have invented certain new and useful 5 Improvements in Wire-Supporting Clamps; and I do hereby declare that the following is a full, clear, and exact description thereof, reference being had to the accompanying drawings, and to the letters of reference marked 10 thereon, which form a part of this specification.

This invention relates to wire supporting clamps, being designed more particularly for use in supporting trolley-line wires for electric railways, although obviously adapted for use in other connections, and has for its object to remedy certain defects which are found to exist in clamps of this character as ordinarily constructed. These clamps are usually and preferably constructed of brass or other alloys of copper, and being of considerable length, with the clamping force applied to the central portion only, the end portions, owing to their distance from the point at which the clamping force is applied and to the comparative weakness of the alloy of which they are constructed, are apt to become separated by the downward strain of the wire, and when the said end portions have separated to an extent sufficient to permit the passage between them of a portion of the wire, the clamping devices can no longer withstand the wedging action of the wire which results, and the wire tears itself free from the clamps. In order to overcome this defect, these clamps have been constructed of steel or some other metal stronger than the alloy usually employed. This construction is objectionable for the reason that as the trolley-wheel passes from the 40 copper line-wire to the steel clamp, "sparking" occurs. To remedy the defect in strength just pointed out without incurring the dangers and disadvantages of this sparking is the object of my present invention, and to this 45 end the said invention consists in certain novel features which I will now proceed to describe, and will then particularly point out in the appended claims.

In the accompanying drawings: Figure 1 50 represents a perspective view of a construction embodying my invention in one form. Fig. 2 is an elevation of one half of the clamp,

showing the inner face thereof. Fig. 3 is an end elevation, partly in section. Fig. 4 is a view similar to Fig. 3, illustrating a modified 55 form of my invention. Fig. 5 is an end elevation of the clamping jaws, detached.

In the said drawings, A and A' represent the two clamping jaws of the support, constructed of brass or other suitable alloy, and 6c having flat inner contact surfaces, the former provided with a dovetail groove, a, extending longitudinally of its inner face, and the latter provided with a corresponding dovetail projection, a', to engage and fit said groove. 65 Each of said jaws is provided in the lower portion of its inner face with a groove, a², the two grooves forming, when the jaws A A' are united, an almost cylindrical conduit in which the wire, W, is clamped. These grooves a² are 70 preferably somewhat less than semi-circular in cross section, so as to embrace the wire W from above to a point somewhat below its middle, leaving a portion of its lower face exposed, as shown, and as is usual in devices 75 of this description. The upper portion of each jaw A A' is provided with a semi-cylindrical shank, a³, threaded on its outer or curved surface, the two forming, when united, a threaded cylindrical shank. This shank is 80 adapted to screw into a threaded socket, B, which is hinged by means of a pivot bolt or pin, b, to a threaded shank, C, which screws into the insulator, D. The parts are assembled by placing the jaws A A' on opposite 85 sides of the wire W end to end, with said wire resting in the grooves a², and then sliding said jaws along the wire in opposite directions, the projection a' engaging the groove a, and when the semi-shanks a³ are opposite 90 each other, they are screwed into the socket B, thus locking the jaws from endwise motion, while the dovetail connection prevents lateral separation of the said jaws, thereby 95 clamping the wire W firmly between said jaws.

It will be noted that the force preventing the separation of the jaws when properly engaged is just as strong at the ends of said jaws as at the intermediate portions, from 100 which it follows that the danger of the separation of the ends of the jaws hereinbefore pointed out as incident to the ordinary construction is entirely obviated, while at the

same time the material most advantageous for preventing sparking may be employed in the construction of the clamp.

It will at once be obvious that my invention is in no wise limited to the particular means shown for connecting the wire clamping jaws with their supporting devices. The hinged construction shown is desirable, and is commonly employed in straight line work for the reason that it equalizes the strain on the jaws and thereby tends to prevent wear. The jaws may, however, be screwed directly into the insulator, or otherwise supported. Moreover, although the threaded shank and socket device shown and described form a desirable and convenient means for preventing longitudinal movement of the jaws relatively to each other when in place, yet I do not limit myself to this construction, as other means for effecting this result will readily suggest themselves, and in Fig. 4 I have shown a modification in which the threaded shanks on the jaws are dispensed with, said jaws being provided with unthreaded shanks, a^4 , connected with a bifurcated shank, E, screwed into the insulator D by means of a pivot bolt, a^5 , which serves to prevent relative longitudinal movement of the jaws A A'. Nor is my invention limited to the precise form of dovetail connection shown, since it is obvious that other forms of male and female connection may be substituted therefor, and the engaging device need not be continuous, as in the construction shown.

What I claim is—

1. The combination, with a wire to be supported, of clamping jaws adapted to engage and support said wire and respectively pro-

vided with a dovetail groove and corresponding projection extending the entire length 40 thereof, and means for preventing relative longitudinal movement of the said jaws when in position, substantially as described.

2. The combination, with the jaws A A', having male and female connecting devices 45 adapted to be engaged by relative longitudinal movement of said jaws, and each provided with a semi-cylindrical externally threaded shank, of a threaded socket to receive the said threaded shanks when in position, substantially as described.

3. The combination, with the jaws A A', adapted to clamp the wire, provided respectively with a dovetail groove a and corresponding projection a' , and each having a semi-cy- 55 lindrical externally threaded shank, of a correspondingly threaded socket to receive said threaded shanks, an insulator, and a shank secured to the insulator and pivoted to the socket, substantially as described. 60

4. The combination, with a wire to be supported, of clamping jaws provided with grooves forming a recess to receive the wire, said jaws having respectively a groove and a projection to engage therewith parallel with said recess, 65 and means for holding said jaws in position with their said groove and projection in such engagement to prevent lateral separation of the jaws, substantially as described.

In testimony that I claim the foregoing as 70 my invention I affix my signature in presence of two witnesses.

A. HELMER ENGLUND.
